PRESSING IRON

Samuel Dowinsky, New York, N. Y.

Application November 15, 1933, Serial No. 698,198

4 Claims. (Cl. 68—26)

This invention relates to pressing devices of the type known as smoothing or sad irons, and more particularly to such as are used in industrial establishments in the pressing of articles, such as clothing, etc.

The common variety of such irons are ordinarily heated upon a gas or electric stove, or by the use of gas in the body of the iron. In such cases, it is often necessary to apply moisture to the article being pressed, so as to enable the operator to complete the operation satisfactorily.

The present invention has as an object to provide a smoothing iron of the usual shape adapted for normal operation and provided with an internal heating means readily controllable with respect to its temperature and supplied from any convenient source of electrical energy.

A further feature is in the provision of means whereby the article operated upon may be slightly moistened to a desired extent as the work progresses.

Another aim is to provide effective control means for emitting such moisture in the form of steam, the control means being readily actuated by an operator without removing the iron from the article while being pressed, or without the operator removing the hand from the handle of the iron.

A still further purpose is to provide a simple, compact smoothing iron, readily operated and of such weight and proportions as may be preferred.

These and other advantageous objects are accomplished by the novel construction, arrangement, and combination of parts hereinafter described and shown in the accompanying drawings, forming an essential part of this disclosure, and in which:

40 Figure 1 is a top plan view of a smoothing iron made in accordance with the invention, parts being broken away to show its construction.

Figure 2 is a transverse sectional view taken on line 2—2 of Fig. 1.

45 Figure 3 is a bottom plan view of the iron, drawn to a diminished scale.

Figure 4 is a longitudinal sectional view, taken on line 4—4 of Fig. 1, certain parts being in side elevation.

50 Figure 5 is a transverse sectional view taken on line 5—5 of Fig. 4.

Figure 6 is a longitudinal sectional view taken on line 6—6 of Fig. 7.

55 Figure 7 is a sectional view taken on line 7—7 of Fig. 4 in a horizontal plane.

Figure 8 is a similar sectional view taken on line 8—8 of Fig. 4.

Figure 9 is another like sectional view taken on line 9—9 of Fig. 4.

Figure 10 is a longitudinal sectional view taken substantially on line 10—10 of Fig. 4.

Figure 11 is another similar sectional view taken on line 11—11 of Fig. 4.

Stated in general terms, the iron consists of a lower or base element, generally designated by 10 the numeral 15, having secured on its upper side a cover element 16, having raised pads mounted by turned handle supports 17 for a handle 18.

A removable section 16' of the cover element 16, is provided, the purpose of which will be described hereinafter.

These several elements are secured by threaded studs 19 set in the base 15 to pass through the cover 16 and handle supports 17 which are clamped by nuts 20. Between the base and cover 20 is a closed chamber 21 in which is disposed horizontally spaced metal plates 22—23, respectively upper and lower, the plate 23 having on its lower side a liner 25 of mica or similar material; a similar liner 24 is seated in the bottom of the 25 chamber 21.

These plates are held in their assembled position by reason of the studs 19, which pass through openings appropriately formed therein, while the margins of the plates are adjacent to the walls 30 of the chamber 21, these walls constituting the profile of the smoothing iron, which is of the usual shape.

On the upper side of the plate 22 is a sheet of asbestos 26, a similar sheet 27 being disposed 35 midway in the space between the metal plates 22—23.

Set in the rear portion of the cover element 16, and to one side thereof, is a dielectric block 28 containing a recess 29 in which are disposed electric terminals 30 and 31. The terminal 30 engages a fixed conductor 35, which is in electrical communication with a plurally coiled resistance 36 in the bottom of the chamber 21 between the liners 24—25.

40 Thus it will be seen that when the terminals 30—31 are in circuit, a current is passed through the resistance 36 in the bottom of the chamber, the heat being transferred to the base 15, and other parts of the iron.

50 Arranged in the resistance coil 36 are a series of contacts 37, constituting a rheostat, from each of which extend taps 38 engaged by insulated screws provided with button heads 39, all of which are selectively engageable by a contact 40, car- 55

ried on a lever 41 and controlled by a knob 42 on the free end of the lever, which is mounted on a screw pivot 43 set in a recess in the upper side of the cover 16, thus providing means for controlling the heat transmitted to the iron.

The lever pivot 43 is connected with a conductor 44 disposed in the chamber 21 and is in electrical communication with a conductor 32, which in turn is in communication with the terminal 31.

Disposed in the spaces between the asbestos sheet 27 and the adjacent spaced metal plates 22-23, is a metal coil 45 consisting of thin tubes, parts of the coil being on opposite sides of the sheet 27, the outlet end of the coil 45 having a connection 46 engaged with a downturned elbow 47 set in the base 15 and open to a transverse passage 48 which extends through the forward part of the solid base of the iron, its ends provided with closure plugs 49.

The passage 48 has communicating ducts 50 leading to a similar transverse passage 51, in the rear portion of the base of the iron, which is also provided with plugs 49, to prevent the outlet of steam or moisture.

The passages 48-51 are in communication with other ducts 52, closed at their rear ends and arranged convergently toward the front of the iron; the ducts 50 having plugs 53 at their outer rear ends.

Plugs 48' are disposed in the duct 48 adjacent the inner walls of the ducts 52 to force the steam or moisture rearwardly through the ducts 50, thence through duct 51 into the ducts 52.

The ducts 52 are provided with a plurality of fine perforations 54 formed in the bottom wall of the base 15, for the escape of steam and moisture upon the surface of the material being operated upon with the iron.

The inlet end of the coil 45 is connected by a raised coupling 56, with a bore 58 in an inreaching plug 57, extending from a block 60 and in which is a check valve 55 to prevent the return of water, the passage 59 being closed at its outer end by a screw plug 61. The screw plug 61 set in the rear portion of the block 60 carries on its inner end a rod 94, the top 95 of which is flattened, thus providing a narrow passage to insure a regulated flow of water into the bore 58. The detachable cover plate 16', in the cover element 16, is provided so as to render ready access to these elements should such necessity arise.

The block 60 is secured on the rear end of the iron by bolts 62, which also serve as plugs for the passages 52, and has a transverse opening 63, controlled by a needle valve 64, the stem 69 of which passes upwardly through a boss 65, screw threaded to receive a nut 66, a lock nut 67 intervening.

Set in the nut 66 is a gland 68 to compress packing about the stem 69 of the needle valve 64, this stem being screw threaded at its upper portion 70, and is guided by a sleeve 71 threaded into an arm 72 extending from a bracket 73 fixed by the screw threaded boss 65 on the block 60.

The sleeve 71 is provided with a head 74 and a check nut 75 by means of which the valve stem may be adjusted.

A compression spring 76, abutting at its upper end the extremity of the sleeve 71, acts to force a collar 77, threaded on the stem 69 downwardly, this collar being secured by a lock nut 78.

Fixed in this collar, to extend oppositely outward, are arms 79 adapted to engage the end elements of a fork 80 integral with the rear

end of a lever 81, pivoted at 82 on the bracket arm 72, this bracket being further provided with a forwardly extending arm 83 carrying an adjusting screw 84, provided with a lock nut 85 and adapted to limit the depression of the lever 81, the front end of which is provided with a knob 86.

Extending angularly from the block 60 is a tubular inlet connection 87 reduced at its outer end to receive a flexible tube 89 connected with a 10 water supply which, from the foregoing, is obviously controlled by the needle valve 64.

It is to be noted in Figure 5 that the outer tube in the coil 45 passes through the rear wall of the iron into a chamber 90, formed in the lower part 15 of the block 60, where it is provided with connections 91, including a check valve 92; also, another similar check valve 93 is disposed in the upper coil 45, as seen in Fig. 8.

The usual guard 33, for receiving the electric 20 cord plug, is provided on the rear handle support 17.

In operation, the lever 81 is depressed to allow a limited quantity of water to pass the end of the needle valve 64, into the passage 59, past 25 the first check valve 58, and into the heated tube 45, where, due to the high temperature of the tube coil, it is converted into steam to continue therethrough past the check valves 92 and 93, into the ducts and out through perforations 54 onto the 30 article being operated on.

Upon release of the lever 81, the water is prevented from entering the heated tube coils, thus stopping the flow of steam from the perforations 54. The amount of steam for moistening the 35 article operated on is very limited, usually for a period of but several seconds, after which the hot dry iron is used to complete the operation on that particular portion of the article being pressed. Therefore, it is imperative that the 40 amount of water allowed to enter the heated coil be accurately and quickly controlled, which, with the present device, is possible.

Although the foregoing is descriptive of the preferred embodiment of the invention, it will be 45 apparent that minor changes may be made in its construction, without the exercise of invention or departing from the scope of the claims hereto appended.

Having thus described the invention, what is 50 claimed as new and desired to secure by Letters Patent, is:

1. In a pressing iron, a chambered body containing a heating means, means to control the heating means, communicating pipe sections arranged to form an upper and a lower layer in the chamber of said body above said heating means, heat insulating elements interposed between, above and below the pipe layers, controllable means for the inlet of water to the upper layer, a 55 series of ducts in said body below the chamber, said chamber having perforations in its bottom wall, and connections between said ducts and the lower layer.

2. In a pressing iron having a body comprised of upper and lower sections, forming an enclosed chamber therebetween, heating means in the bottom of said chamber, a pipe coiled in said chamber adjacently above said heating means, a second coil thereover connected at one end to the first named coil, ducts in the bottom wall of said body in communication with the lower coil, said ducts having a plurality of perforations leading through the bottom of said body, means to 75

controllably admit minute quantities of water to the first named pipe coil, both of said coils being disposed in level planes, and a heat insulating plate between said coils.

5. 3. In a pressing iron having a body comprised of a handle, upper and lower sections forming an enclosed chamber therebetween, heating means in the bottom of said chamber, a pipe coiled to produce flat upper and lower layers in said chamber adjacently above said heating means, check valves in said pipe layers, ducts in the bottom wall of said body communicating with the lower coil, said ducts having a plurality of perforations leading through the bottom of said body, means 10 to control said heating means, and means to

controllably admit minute quantities of water to the upper pipe coil, said control being adjacent said handle.

4. In a pressing iron, a chambered body having a controllable heating means therein, a pipe coiled in layers in said body above said heating means, said layers being flat and heat insulated from each other, controllable means for the inlet of water to the upper layer of the pipe coil, a series of ducts in said body below the chamber, perforations in the bottom wall of said chamber leading to the ducts, and a connection between said ducts and the lower layer of said pipe coil.

SAMUEL DOWINSKY. 15
